(57) **CLAIM**

The ornamental design for a driveline socket, as shown and described.

DESCRIPTION

FIG. 1 is a front perspective view of the driveline socket according to a first embodiment of the present design;

FIG. 2 is a bottom plan view of the driveline socket as shown in FIG. 1;

FIG. 3 is a top plan view of the driveline socket as shown in FIG. 1;

FIG. 4 is a rear elevation view of the driveline socket as shown in FIG. 1;

FIG. 5 is a front elevation view of the driveline socket as shown in FIG. 1;

FIG. 6 is a left side elevation view of the driveline socket as shown in FIG. 1;

FIG. 7 is a right side elevation view of the driveline socket as shown in FIG. 1;

FIG. 8 is a front perspective view of the driveline socket according to a second embodiment of the present design;

FIG. 9 is a bottom plan view of the driveline socket as shown in FIG. 8;

FIG. 10 is a top plan view of the driveline socket as shown in FIG. 8;

FIG. 11 is a left side elevation view of the driveline socket as shown in FIG. 8;

FIG. 12 is a right side elevation view of the driveline socket as shown in FIG. 8;

FIG. 13 is a front elevation view of the driveline socket as shown in FIG. 8; and,

FIG. 14 is a rear elevation view of the driveline socket as shown in FIG. 8.
